BENJAMIN HOLT, OF STOCKTON, CALIFORNIA.

ENDLESS-CHAIN TRACK FOR TRACTORS.

1,314,649.

Specification of Letters Patent. Patented Sept. 2, 1919.

Application filed August 15, 1916. Serial No. 115,071.

To all whom it may concern:

Be it known that I, BENJAMIN HOLT, a citizen of the United States, residing at Stockton, in the county of San Joaquin and 5 State of California, have invented new and useful Improvements in Endless-Chain Tracks for Tractors, of which the following is a specification.

This invention relates to endless chain 10 tracks for use in vehicles or tractors of the self-laying track type.

My object is to improve and simplify the construction of a chain track of this type, with a view particularly, to produce a lightened form thereof, which will at the same 15 time be economical to manufacture and possess the desired strength and durability to withstand the hard usage to which it is put in operation.

20 One form which my invention may assume is exemplified in the following description and illustrated in the accompanying drawings in which—

Figure 1 is a perspective view of a track 25 shoe and link embodying my invention.

Fig. 2 is a longitudinal section.

Fig. 3 is a transverse section.

Fig. 4 is a plan view of a plurality of said links connected together.

30 Figs. 5 to 10 illustrate in successive steps the manner of forming one of the side bars from a blank.

The endless track is made up of a series 35 of articulated link sections, each embodying a pair of parallel side bars 10. Each bar has a struck-up flange 11 at its inner longitudinal edge and a similar flange 12 at its outer longitudinal edge, formed by punching and pressing the material of the central 40 portion of the body of the bar into position at right angles to the vertical plane of the bar. While adjacent links of the track are of different width and have their flanges extending in different directions, only one form 45 of side bar 10 is necessary. Alternate links are formed by detachably connecting the parallel side bars by gudgeon pins 13 entering elongated openings 14 in the ends of the bars. The side bars of this link are positioned so that their flanges extend outwardly 50 away from each other, as shown in Fig. 1, while intermediate links or those connecting with the one already described, have their side bars reversely arranged so that the 55 flanges extend inwardly or toward each

other. The connection between successive links is made by journal pins 15 secured in the side bars and passing through axial openings in the gudgeon blocks 13. Adjacent links have their side bars overlapping so 60 that the flanges 11, in coaction with the overlapping ends of adjacent links produce a continuous track, as shown in Fig. 4 to receive and support the roller truck mechanism of the tractor.

65 The outer flanges 12 are drawn out in a vertical plane from the edge of the side bar as at 26 to produce an arch-like construction and to space the flange away from the ends of the bar. To these flanges 12 of each link, 70 a pressed metal shoe 16 is secured, said shoe being substantially rectangular in form and having pressed ribs 17 on its outer surface, which constitute gripping members for engagement with the ground. Channels corresponding to the ribs are left on the inner side of the shoe and these are filled by wooden pillows 18, said pillows being preferably a little higher than the intermediate portion 19 of the shoe. Over these pillows 80 lies a spring metal plate 20, upon which the flanges 12 rest, and by means of bolts 21 extending through the flanges and shoe, the parts are clamped together with the plate 20 held under tension with its intermediate 85 portion engaging with the portion 19 of the shoe. The surfaces of the flanges 12 rest on the plates 20 between the points where the plates rest on the pillows 18, so that a limited cushioning action may take place. 90 Moreover, the constant tension of the plate 20 tends to move the link and shoe apart, and the nuts on the bolts 21 are retained in place without the use of a lock. It will be noted that the parts are retained tightly in engagement even as against wear, and thus the danger of the bolts becoming sheared off through slight relative movement between the shoe and link is overcome. The wooden pillows reinforce the interior of the ribs 17; 100 they are light and therefore add little to the weight of the shoe; and, as pointed out, afford a certain degree of cushioning action that is desirable. As shown, a transverse brace plate 22 may be utilized in the connections between the link and shoe, resting upon the inner surfaces of the flanges 12 and being held in place by the nuts on the bolts 21. This plate has its ends bent down over 105 the outside of the flanges, thus holding the 110

side bars firmly against any tendency to spread apart. The bolts 21 preferably bridge the opening in the side bars to form a transverse brace between the two flanges.

5 The ends of shoes of adjacent links are designed to overlap, as shown in Fig. 2, where 16^a indicates the ends of adjacent shoes but in assembling the parts, the shoes on the links having the gudgeon blocks 13 are placed on the inside or next to the gudgeon blocks. This construction enables one to employ a simple and effective means for supplying lubricant to the bearing in the block, it only being necessary to provide 10 a trough-like receptacle 30, which is located in position against the gudgeon block between the side bars where it is held by the end of the shoe. The trough-like receptacle supplies lubricant to the internal bearing through a slot or openings in the gudgeon block and it is conveniently filled with lubricant through openings 31 located on the inner side or next the center of the link.

15 The trough-like receptacle not only serves as a lubricant supply, but it is an additional support for the end of the shoe and when employed it becomes practical to dispense with the use of the pillow blocks in these links.

20 30 The receptacle 30 is preferably made of metal the side walls of which will yield slightly under the pressure of the shoe, whereby it will be retained firmly in place when the shoe is adjusted to its position.

25 35 As to the manner of constructing the side bars 10, this is shown in successive steps in Figs. 5 to 10. A blank 23 shown in Fig. 5 is first punched to form transverse slots 24, shown in Fig. 6. The blank is then sawed 40 along a longitudinal, central line 25, as in Fig. 7, and thereafter the severed members are punched outwardly to the position shown in Fig. 8 to form the flanges 11 and 12. Thereafter the flange 12 is drawn outwardly, 45 as shown in Fig. 9, to space the same in a vertical direction from the edge surface of the adjacent ends. Outwardly converging webs 26 are thus formed, extending from the body portion of the bar to the flange 12, and these offer an arched support for the 50 flange, in addition to permitting spacing of the ends of the bar from the shoe when the parts are assembled.

55 Such a construction as is herein shown and described is decidedly economical to manufacture. The parts being detachable and separable throughout, are easily replaced at slight expense.

60 There is but one shape of side bar 10 necessary, and the different arrangements of the links are obtained by transposing the position of the side bars and spacing them closer or farther apart, depending upon whether they are used in embracing of embraced links. The punching of the flanges

11 and 12 from the body portion of the links provides open sides which are important to prevent trapping of mud between the links.

65 While I have shown and described herein but one form of my invention, it will be understood that various changes in the construction and arrangement of the several parts may be employed without departing from the spirit thereof.

70 What is claimed is:—

1. An endless track for tractors comprising a series of articulated link sections, a shoe bolted to each link, and a pressure device between the link and shoe to retain the connections tightly engaged. 75

2. An endless track for tractors comprising a series of articulated link sections, a shoe bolted to each link, a spring plate between the shoe and link under tension to retain the connections in close engagement. 80

3. An endless track for tractors comprising a series of articulated link sections, a shoe bolted to each link, a spring plate between the shoe and link under tension to retain the connections in close engagement, 85 said spring plate pressing outwardly at its ends against the shoe and inwardly at its central portion against the link.

4. In an endless chain track for tractors, a link section, a shoe carried thereby, said shoe having pressed ribs formed on its outer surface, wood fillers carried in the channels formed by said ribs and a spring plate resting on said fillers and held under tension against the intermediate portion of the shoe 90 by the link. 95

5. In an endless chain track for tractors, a link, a shoe carried thereby, said shoe having pressed ribs formed on its outer surface, leaving channels on its inner surface, wood 105 fillers in said channels and a metal plate between the shoe and the link, engaging and retaining the fillers in place.

6. An endless chain track for tractors comprising a series of articulated link sections, each formed with parallel side plates provided with straight flanges on their outer longitudinal edges, a shoe bolted to said flanges and a pressure plate between said shoe and flanges. 110

7. A link section for a tractor chain track embodying side bars and tubular blocks connecting said side bars and having openings intermediate the ends, removable shoes secured to the side bars, trough-like receptacles forming supports for the ends of the shoes and bearing against the said blocks on opposite sides of the intermediate openings, said trough-like receptacles having openings in the inner walls for the introduction of lubricant. 115

8. A link section for a tractor chain track embodying side bars and a tubular gudgeon block connecting the side bars at each end of the link, said blocks having transverse open- 120

125

ings intermediate the ends, a shoe secured to the side bars and having ends projecting beyond the gudgeon blocks and a trough-like receptacle clamped between each end of the 5 shoe and the gudgeon block at the corresponding end of the link section, said receptacle bearing on the block at each side of the transverse opening in the blocks and having an opening for the introduction of lubricant.

10. 9. A link section for a tractor chain track embodying side bars having inner and outer flanges, a shoe supported by the outer flange and a bolt for connecting said shoe and flange bridging the space between the flanges 15 and forming a brace therefor.

10. A link section for a tractor chain track embodying independent side bars, pivot connection interposed between the opposite ends of the side bars, a shoe supported by the 20 outer edge of the side bars, a tie plate bridging the space between the side bars and having its ends bent to embrace and tie the side bars together and fastening bolts passing through the tie plate, side bars and shoe for 25 securing the parts in position.

11. An endless track for tractors, comprising a series of articulated link sections, a shoe carried by each link, and combined cushioning and tension means interposed between the shoe and the link.

12. An endless track for tractors, comprising a series of articulated link sections, tread plates carried by the sections, depressions in said plates forming ribs on the exterior and 35 channels on the interior thereof, and cushioning means carried in said channels and between the links and the tread plates.

13. An endless track for tractors comprising a series of articulated link sections, shoes 40 carried by each link, spaced receptacles formed on the interior of the shoes, and cushioning means carried in said receptacles and between the shoes and the links.

14. An endless track for tractors compris-

ing a series of articulated link sections, shoes 45 carried by the links, and tension plates interposed between the shoes and the links.

15. In an endless chain track for tractors, a link section, a shoe carried thereby, said shoe having pressed ribs formed on its outer 50 surface, cushioning means carried in the channels formed by said ribs, and a tension member interposed between the shoe and the link and resting on said cushions.

16. An endless track for tractors, comprising a series of articulated link sections, shoes carried by said links and overlapping each other at their contiguous ends and tensioning means adapted to maintain a close joint between the overlapping surfaces of said 60 shoes.

17. An endless track for tractors, comprising a series of articulated link sections, shoes carried by said links and overlapping each other at their contiguous ends and tensioning means adapted to maintain a close joint between the overlapping surfaces of 65 said shoes and non-metallic members interposed between the opposite ends of said tensioning means and the shoes, whereby limited resilient movement may be effected between said shoes and said tensioning means.

18. An endless track for tractors comprising a series of articulated link sections, a spring plate beneath each of said sections, a 70 shoe carried by each of the links and adapted to be secured over the spring plate and non-metallic cushion members interposed between the opposite ends of the spring plate and the shoe.

In testimony whereof I have hereunto set my hand in the presence of two subscribing witnesses.

BENJAMIN HOLT.
